[57] CLAIM

The ornamental design for a bluff body flowmeter, as shown.

DESCRIPTION

FIG. 1 is a top, front, and right side perspective view of a bluff body flowmeter showing my new design, which is shown on a reduced scale;

FIG. 2 is a top plan view which is shown on an enlarged scale in FIGS. 2 through 5;

FIG. 3 is a left side elevational view;

FIG. 4 is a bottom plan view; and,

FIG. 5 is a rear elevational view thereof.
